PASTE DISPENSER WITH CAP

William J. Ziegler, Clarks Summit, Pa.

Application February 6, 1939, Serial No. 254,927

4 Claims. (Cl. 221—60)

The object of my invention is to provide a novel paste tube dispenser for conveniently and effectively expelling paste from the tube; and to provide a novel cap or applicator attached to the nozzle of the paste tube to cause a straight flow of the paste without curling, and to stop the flow of paste when operation of the device ceases. It is also an object of my invention to provide the novel combination and arrangement of parts in a device of this type, as shown and described.

I attain these and other objects of my invention by the mechanism illustrated in the accompanying drawings, in which—

Figure 1 is a side elevation of the bracket arms and base support, with the shield 22 in reversed position;

Fig. 2 is a top plan view of the same;

Fig. 2a is a top plan view of a modified form of integral bracket arms and base plate;

Fig. 3 is a front elevation of the bracket arms with the rollers removed;

Fig. 4 is a perspective view of the winding roller into which the end U of the paste tube T is being inserted;

Fig. 5 is a vertical section on line 5—5 of Fig. 2, the tube cap being shown in side elevation;

Fig. 6 is a transverse section on line 6—6 of Fig. 5; and

Fig. 7 is an enlarged vertical section through the applicator A.

Fig. 8 is a detail view of roller 15, partly in elevation and partly in section and of shaft 14 in elevation.

Like characters of reference designate like parts in each of the several views.

Referring to the accompanying drawings, W indicates the supporting wall to which the bracket base 1 is fastened by screws 2. T designates a tube of paste, and U its flattened end. B designates a tooth brush; and E designates the expeller device as a unit. A indicates the cap or applicator as a unit.

I provide a bracket base 1 having apertures for screws 2 by which it is fastened to the wall W. Mounted on base 1, (or a part of same, as shown in Fig. 2a) are bracket arms 8. Bracket arms 8 are curved outwardly at 7, as shown in Figs. 1 and 3, and terminate in enlarged ends 9 which are provided with vertical slots 10 to receive a slotted winding roller 17, as shown in Figs. 1 and 2. One or more suitable hooks 5 may be formed on or affixed to the bracket base 1 for holding tooth or other brushes B.

I provide diagonally disposed elongated slots 11 to receive the pressure roller 12 retained on bracket arms 8 by suitable heads 13, the function of the diagonally disposed slots being to increase pressure exerted by rollers 15 and 12 on the paste tube. I also provide a loosely mounted, revoluble hollow squeezing roller 15, extending from the inside surface of one bracket arm 8 to the inside surface of the other bracket arm 8. Roller 15 is mounted on stationary shaft 14 which has an end knob 14a at one end and is screwed into a suitable tapped and threaded aperture in the opposite bracket arm 8. This construction facilitates removal of the paste tube from the device.

Winding roller 17 has a slot 18 to receive the flattened end U of the tube T of paste or other material to be expelled from the tube. The end 19 of the winding roller 17 is secured to a head 16 and is seated in the slots 10 of arms 8. Roller 17 also has a finger key 20 at its other end for operating the roller.

Bracket arms 8, as shown in Figs. 1 and 5, are braced by a spacing bolt 21. Swingably mounted on the spacing bolt 21 is a cover or shield 22 extending the full width of the entire dispenser, and having an upstanding fin or piece 23 by which the shield may be conveniently raised when not in use. When closed the shield seats on the top surfaces of bracket arms 8.

Referring to Fig. 7, I provide a knurled or hexagonal channelled thumb piece 25 which is screw-threaded at 26 for screw-threaded engagement on the conventional threaded nozzle 24 of a paste tube T, member 25 terminating in a depending tube 27. Depending tube 27 preferably has its lower end threaded at 28 for engagement by a base washer 29 screw-threaded on said threaded lower end. To the washer 29, the depending support 30 is fastened by solder or rivets 31 or by other suitable means. Support 30, in turn carries a check valve 33, which may be spherical or of other suitable shape, secured to it by solder 32 or otherwise suitably affixed, and spaced from the lower end of depending tube, as shown in Fig. 7. Valve 33 removably seats on the valve seat 34 to open and close the passageway. The nozzle extension 35 provides a longer passageway for the paste (which prevents curling of the paste). The body 36 is detachably affixed to a top 38 which loosely engages tube 27 to permit of vertical sliding movement relative thereto, and the top 38 has a threaded depending flange 37 screw-threaded to the upper end of the body 36, as shown in Fig. 7. Positioned above washer 29 is suitable packing 40, above which is a protecting follower or washer 41 on which a coil 55

spring 42 seats. This coil spring extends from member 41 to the pressure top 38 of the applicator, and presses against both of those members.

To operate the device, the conventional cap is removed from the paste tube and my dispenser cap or applicator A is screw-threaded on the nozzle of the paste tube in its place, the base end U of the paste tube T is unwound and is inserted into the slot 18 in winding roller 17 and a half-turn is made. The front roller 15 is removed from the ends 9 of arms 8 of the dispenser; member 14 being detachable to admit of the withdrawal of this roller. The tube of paste is then placed in position and the front roller 15 is replaced in its proper position in the arms to engage the end of the paste tube. By winding the finger key 20 and the winding roller 17 which it operates the roller 12 approaches roller 15 until only the thickness of the front and back walls of the paste tube separate them. As the paste tube is drawn through rollers 15 and 12 the paste is forced downward to the cap end of the tube and into the cap or applicator A. The pressure of the paste forced into the lower end of the body 36 forces that member downward away from the valve 33 and against the pressure of spring 42 to create a passage between ball valve 33 and its seat 34. The paste emerges until pressure is released by stopping the operation of the finger key 20 and its roller whereupon the coil spring 42 bearing against top 38, which is affixed to the upper end of the body 36, will force body 36 upward until the ball valve 33 against rests on its valve seat 34, thereby stopping the flow of the paste. When it is desired to replace a paste tube from which the paste has been ejected with a new full paste tube, the shield 22 is lifted, as shown in dotted lines in Fig. 5, to permit access to the old paste tube and the roller 12 is slid downwardly in the elongated slots 11 to permit of readily withdrawing the flattened end of the tube as it is unwound from the roller 17 for replacement by a new full tube of paste.

What I claim is:

1. In a device of the type described, the combination of a base adapted to be affixed to a wall, spaced bracket arms mounted on the base, the bracket arms having opposite vertical slots and opposite diagonally disposed slots, a slotted roller 50 removably mounted in the vertical slots and having an operating element at one end, said roller being adapted to engage the unfolded end of the paste tube, a pair of slightly spaced rollers positioned below the aforesaid slotted roller to engage and squeeze the tube, one of said rollers being mounted in diagonally disposed slots in the bracket arms whereby to increase pressure exerted by the rollers on the paste tube and to be readily disengaged from the paste tube to permit of withdrawing same from the device when

empty, and a swingably mounted shield normally covering and concealing the aforesaid rollers.

2. In a device of the type described, the combination of a base adapted to be affixed to a wall, diverging bracket arms extending from said base, the bracket arms having opposite vertical slots and opposite diagonally disposed slots, a slotted roller removably mounted in the vertical slots and having an operating element at one end, said roller being adapted to engage the unfolded end of the paste tube, a pair of slightly spaced rollers positioned below the aforesaid slotted roller to engage and squeeze the tube, one of said rollers being mounted in diagonally disposed slots in the bracket arms whereby to increase pressure exerted by the rollers on the paste tube and to be readily disengaged from the paste tube to permit of withdrawing same from the device when empty, the other roller being hollow and revolvably supported, and a swingably mounted shield normally covering the device.

3. In a device of the type described, the combination of a base adapted to be affixed to a wall, diverging bracket arms affixed to the base, the bracket arms having opposite vertical slots and opposite diagonally disposed slots, a slotted roller removably mounted in the vertical slots and having an operating element at one end, said roller being adapted to engage the unfolded end of the paste tube, a pair of slightly spaced rollers positioned below the aforesaid slotted roller to engage and squeeze the tube, one of said rollers being mounted in diagonally disposed slots in the bracket arms whereby to be readily disengaged from the paste tube to permit of withdrawing same from the device when empty, and a swingably mounted shield normally covering the aforesaid rollers.

4. In a device of the type described, the combination of a base adapted to be affixed to a wall, diverging bracket arms extending from said base, the bracket arms having opposite vertical slots and opposite diagonally disposed slots, a slotted roller removably mounted in the vertical slots and having an operating element at one end, said roller being adapted to engage the unfolded end of the paste tube, a pair of slightly spaced rollers positioned below the aforesaid slotted roller to engage and squeeze the tube, one of said rollers being mounted in the diagonally disposed slots in the bracket arms, the other roller being hollow and revolvably supported, a stationary shaft on which said roller is mounted, said shaft being threaded at one end and having said end engaging the bracket, and a knob on the other end of said shaft to permit of its removal to facilitate removal of the paste tube from the device.
